UNITED STATES PATENT OFFICE.

JOHN HENRY BIRCH AND JOHN HAYS BIRCH, OF CRAWFORDSVILLE, INDIANA

GAS-ENGINE.

No. 883,688.

Specification of Letters Patent.

Patented April 7, 1908.

Application filed October 4, 1907. Serial No. 395,886.

To all whom it may concern:

Be it known that we, JOHN HENRY BIRCH and JOHN HAYS BIRCH, citizens of the United States, residing at Crawfordsville, in the county of Montgomery and State of Indiana, have invented certain new and useful Improvements in Gas-Engines, of which the following is a specification.

The object of our invention is to produce an exhaust valve mechanism for internal combustion engines of such character that the exhaust valve will be intermittently operated by the pressure within the cylinder and will be held open by that pressure until automatically released by a properly timed mechanically operated valve.

The accompanying drawings illustrate our invention: Figure 1 is a vertical section of an engine embodying our invention; Fig. 2 a similar section of the cylinder and associated parts at right angles to the section Fig. 1; and Fig. 3 a plan with the cap removed.

In the drawings, 10 indicates a power cylinder and 11 a power piston mounted therein, said piston being connected by a pitman 12 with a crank 13 carried by the crank shaft 14. Leading into the end of the cylinder 10 is an inlet passage 15 the inner end of which is controlled by a puppet inlet valve 16. Leading from the same end of cylinder 10 is an exhaust passage 17 closed by an inwardly opening exhaust valve 18 normally held closed by a spring 19. Secured to the outer end of the stem of valve 18 is a piston 20 which fits within the cylindrical piston-valve chamber 21 formed in the head 22 which closes the end of cylinder 10. Head 22 has formed in it the inlet and exhaust passages and also carries the valve 16 as well as the valve 18 and said head 22 is preferably open at its outer end to facilitate the formation of the water chamber 25, the cylinder 21, the bore for the stem of valve 16, and the various other passages which will be herein-after described. The open end of head 22 is closed by an easily removable cap 26, the openings 25 extending axially through it in order to communicate with the water space 28 surrounding the cylinder 10. Communicating with the outer end of the valve cylinder 21 is one end of a passage 29, which extends diagonally through head 22 and com-

municates at its lower end with a pipe 30 which extends downwardly through the water jacket 28, and communicates at its lower end with a passage 31 which, in turn, communicates with the chamber 32 formed in a casting 33, secured to the side wall of cylinder 10. Formed at one side of chamber 32 is a valve seat 34 in which is fitted a check valve 35, normally held in its seat by spring 35', the valve seat leading to a passage 36 which communicates with the passage 37. The passage 37 passes through the wall of cylinder 10 into said cylinder at the end of the power stroke of piston 11. Leading from passage 36 is a passage 38 which communicates with a passage 39 formed through the wall of cylinder 10 beyond the passage 37 and in such relationship that, when the piston is at the upper end of its stroke, passage 39 will be in communication with the crank base 40 which is not air-tight, but said passage will be closed by the piston when the passage 37 is opened into the cylinder 10.

For the purpose of mechanically operating valve 35, we provide a reciprocating pin 41 which, at one end, engages the stem of valve 35, so as to drive it in one direction against the action of spring 35' and, for convenience and economy of construction, at its other end carries the plunger 42 of a pump 43. Pin 41 is connected by a link 44 with the strap 45 of an eccentric 46 secured to and rotated with the crank shaft 14.

The operation is as follows: With the parts in the positions shown in Figs. 1 and 2, the first down stroke of piston 11 draws in a charge through the inlet passage 15 past valve 16, the spring of said valve being weaker than spring 19 so that the exhaust valve does not move. On the return up stroke the charge, which has just been drawn in, will be compressed and then ignited. The next down stroke of the piston is therefore a power stroke, and when the end of the power stroke is reached a portion of the pressure within the cylinder will pass through passage 37 past valve 35, said valve opening under the pressure, and through passages 31, 30 and 29 into the outer end of the valve cylinder 21, so as to act upon the piston 20 and force exhaust valve 18 inward from its seat so as to open the exhaust passage 17. The

exhaust valve is thus held open during the next return stroke of the piston so that the exhaust gases are driven out from the cylinder. Just as the power piston reaches the 5 upper end of its stroke of return following the power stroke, eccentric 46 operates to mechanically open valve 35, whereupon the pressure in the chamber 21 is allowed to escape through passages 38 and 39 into the 10 crank base 40 so as to permit spring 19 to close the exhaust valve 18. It will be seen by the above that the piston is not depended upon to close the ports to maintain the pressure against the exhaust - valve - operating 15 piston but that, instead, the pressure against said valve-piston, being once admitted by the movement of the power-piston, is held by the wholly separate valve 35 which may be small and easily maintained tight. As a consequence, the exhaust valve will be held open by the admitted pressure as long as may be desired, depending upon the mechanical operation of the retaining valve. At the end 20 of the suction stroke there will be no actuation of the exhaust valve because, at the uncovering of passage 37 by the power piston, on this stroke, there will be no pressure, beyond atmospheric, in cylinder 10, and consequently there will be no opening of valve 25 35 and no pressure passing into the outer end of chamber 21.

We claim as our invention:—

1. In an internal combustion engine, the combination, with a power cylinder and piston therein, of an exhaust valve controlling an exhaust passage leading from said cylinder, yielding means for normally holding said exhaust valve closed, a coöperating valve-piston and cylinder for said exhaust valve, a 35 passage being provided between said cylinder and the power cylinder to admit pressure to the valve cylinder at the end of the power stroke of the power-piston, a valve in said passage arranged to retain pressures within 40 the valve cylinder, and a means controlled by the power-piston for operating said last-mentioned valve.

2. In an internal combustion engine, the combination, with the power cylinder and 50 the power piston, of an exhaust valve controlling an exhaust passage leading from said cylinder, a spring for normally closing said valve, a valve-piston and cylinder for actuating said exhaust valve in opposition to said 55 spring, with a passage forming a communication between said valve cylinder and the power cylinder, the said passage being controlled at its power-cylinder end by the power piston, a check valve arranged in said last-mentioned passage to control eduction 60 from the valve cylinder, there being also a passage communicating with said check-valve passage beyond the check valve relative to the 65 exhaust-valve cylinder and controlled at its other end by the power-piston, and a mechanical connection between said check valve and the power piston for intermittently opening said check valve.

tive to the exhaust-valve cylinder and controlled at its other end by the power-piston, 65 and means for intermittently opening said check-valve.

3. In an internal combustion engine, the combination, with the power cylinder and the power piston, of an exhaust valve controlling an exhaust passage leading from said cylinder, a spring for normally closing said valve, a valve-piston and cylinder for actuating said exhaust valve in opposition to said 75 spring, with a passage forming a communication between said valve cylinder and the power cylinder, the said passage being controlled at its power-cylinder end by the power piston, a check valve arranged in said last-mentioned passage to control eduction 80 from the valve cylinder, there being also a passage communicating with said check-valve passage beyond the check-valve relative to the exhaust-valve cylinder and controlled at its other end by the power-piston, 85 a spring for normally holding said check-valve closed, and means for intermittently opening said check-valve.

4. In an internal combustion engine, the combination, with the power cylinder and 90 the power piston, of an exhaust valve controlling an exhaust passage leading from said cylinder, a spring for normally closing said valve, a valve-piston and cylinder for actuating said exhaust valve in opposition to said 95 spring, with a passage forming a communication between said valve cylinder and the power cylinder, the said passage being controlled at its power-cylinder end by the power piston, a check valve arranged in said last-mentioned 100 passage to control eduction from the valve cylinder, there being also a passage communicating with said check-valve passage beyond the check-valve relative to the exhaust-valve cylinder and controlled at its 105 other end by the power-piston, and a mechanical connection between said check valve and the power piston for intermittently opening said check valve.

5. In an internal combustion engine, the 110 combination, with the power cylinder and the power piston, of an exhaust valve controlling an exhaust passage leading from said cylinder, a spring for normally closing said valve, a valve-piston and cylinder for actuating said exhaust valve in opposition to said 115 spring, with a passage forming a communication between said valve cylinder and the power cylinder, the said passage being controlled at its power-cylinder end by the power 120 piston, a check-valve arranged in said last-mentioned passage to control eduction from the valve cylinder, there being also a passage communicating with said check-valve passage beyond the check-valve relative to the 125 exhaust-valve cylinder and controlled at its

other end by the power-piston, a spring for normally holding said check-valve closed, and a mechanical connection between said check-valve and the power piston for intermittently opening said check-valve.

In witness whereof, we have hereunto set our hands and seals at Crawfordsville, Indiana,

ana, this 28th day of September, A. D. one thousand nine hundred and seven.
